UNITED STATES PATENT OFFICE.

WILLIAM ALBERT BRADLEY, OF MOLINE, ILLINOIS, ASSIGNOR, BY MESNE ASSIGNMENTS, TO MOLINE IMPLEMENT COMPANY, A CORPORATION OF ILLINOIS.

PLOW FRAME.

Application filed February 9, 1922. Serial No. 535,149.

To all whom it may concern:

Be it known that I, WILLIAM ALBERT BRADLEY, a citizen of the United States, residing at Moline, county of Rock Island, 5 State of Illinois, have invented certain new and useful Improvements in Plow Frames, of which the following is a specification.

The invention relates to a plow frame. It is employed in connection with tractor 10 plows of the frameless type.

In plows of this type, the plow beams are connected together by braces which unite the beams into a framework that may be called the frame of the plow, although the plow is often referred to as a frameless plow owing to the fact that there is no frame other than the framework formed by the beams themselves. The goal toward which all manufacturers are striving is to 20 devise a structure that is simple, light and inexpensive, yet rigid, strong and durable so that it will withstand the stresses and strains to which it is subjected.

The general object of the present invention is to provide an improved plow frame of the character described.

Other objects and advantages will appear from the specifications and drawings.

An embodiment of the invention is shown 30 in the accompanying drawings in which, Figure 1 is a side elevation of the plow frame.

Figure 2 is a plan view.

The frame comprises two plow beams 1 and 2 connected by a front brace 3 and a rear brace 4.

The beams are made of flat metal bars having a rectangular cross section in contradistinction to the heavy special agricultural 40 I-beam sections that have heretofore been used quite generally. The front ends of the beams are bent downward slightly and the rear ends are also bent downwardly and provided with a plurality of holes 5 for the reception of fastening devices for attaching plow bodies to the beams. One beam is shorter than the other so that the plow bodies will be in staggered relation, a position that is necessary for plowing in order 50 that one plow will not interfere with the other.

When a plow of this type is drawn through the ground a number of different stresses are set up in the beam structure or 55 framework. The beams must be maintained

in their parallel relation and, consequently, there must be some structure for preventing them from moving to or away from one another. There is also a torsional stress set up in the beam structure and, consequently, it must be made to withstand twisting strains. The frame may also be subjected at different times to violent strains tending to collapse it by moving one beam longitudinally relative to the other. For example, 60 if one plow body were to strike a rock, root, stump, or the like, the force exerted by the tractor or other power device would tend to pull the unobstructed beam forward relative to the obstructed one. If the framework is not built to withstand these strains, 65 it will fail under the conditions of practical operation.

Various constructions have been devised for withstanding these various stresses, but most of them have been exceedingly heavy and somewhat complicated in construction. If the framework is made heavy and the mere strength of parts is depended upon 70 to withstand the stresses, the amount of 75 steel in the structure is excessive, which, not only adds to the cost of the implement, but also increases its weight, thereby increasing the draft and making it more cumbersome and unwieldy. Structures have 80 been devised which involve converging the forward ends of the beams to a point and fastening them together, but such structures are expensive and afford a narrow 85 draft hitch which is not always desirable. 90 The present invention is an improvement over anything heretofore produced and it is especially advantageous because a minimum of steel is used, the parts are of simple construction, and yet the structure is very rigid 95 and durable.

The beams are located parallel to one another and, consequently, need not be bent laterally to any special shape for fastening them together.

The front ends are braced by the front brace 3 which is a U-shaped member with one arm of the U connected to one beam and the other arm of the U connected to the other beam. This brace keeps the front ends of the beams in proper spaced relation and prevents to some degree any longitudinal movement of the beams relative to one another.

The front ends of the brace are bent 110

2
downwardly and provided with holes 6 for the reception of fastening devices for attaching a draft hitch.

The rear brace is also a U-shaped member with the arms of the U diverging as illustrated in Figure 2. The base 7 of the U is attached to one beam and the arms of the U are attached to the other beam. This brace, not only keeps the rear ends and centers of the beams in proper spaced relation, but it also serves to effectually prevent any longitudinal movement of one beam relative to the other. It will be readily appreciated that if this latter brace had only one arm there would be very little resistance to longitudinal movement of one beam relative to the other, but, with the two arms, a braced structure is provided in which one arm is under tension and the other under compression whenever any force is exerted tending to move the beams longitudinally relative to each other. Because of the character of this brace, it need not be made unusually heavy. It can be made of a single piece of metal bent to the shape shown. It can be readily attached to the beams by means of rivets extending through holes punched in the beams.

The structure thus provided has been found to be unusually rigid and durable for the weight of the parts required. The cost of the material and the cost of production

have been kept at a minimum. The result is that an implement frame has been produced at a minimum cost having all the desirable characteristics of devices of this kind. 35

It is to be understood that the structure shown is for purposes of illustration only and that variations may be made therein 40 without departing from the spirit and scope of the appended claim.

I claim:

A plow frame having two parallel plow beams made of flat metal bars of rectangular 45 cross section with the bars positioned with their flat faces in substantial vertical planes, one of said beams being longer than the other so that plow bodies attached to their rear ends will be in staggered relation, a U-shaped brace connecting the forward ends of the beams, one of the arms of the U being connected to one beam and the other arm being connected to the other beam, both of said arms extending forwardly and downwardly beyond the ends of the beams to form connections for receiving a draft hitch, and a U-shaped brace having diverging 50 arms connecting the rear ends of the beams, the base of the U being connected to the short beam and the diverged arms being connected to the long beam. 55

In testimony whereof I affix my signature.

WILLIAM ALBERT BRADLEY.
